UNITED STATES PATENT OFFICE.

OTTO ASMUSSEN, OF BROOKLYN, NEW YORK.

COMBINED AUTOMATIC BURGLAR AND FIRE ALARM SYSTEM.

1,145,224.

Specification of Letters Patent.

Patented July 6, 1915.

Application filed March 13, 1913. Serial No. 753,976.

To all whom it may concern:

Be it known that I, OTTO ASMUSSEN, a subject of the King of Denmark, and a resident of Brooklyn, in the county of Kings and State of New York, have invented a Combined Automatic Burglar and Fire Alarm System, of which the following is a specification.

This invention is a system employing a central station or watch house which is electrically connected with a plurality of subscribers' stations, there being devices located at the subscribers' stations, and indicating apparatus at the central station whereby a burglar alarm or fire alarm may be automatically sent in to the central station from any one or more of the subscribers' stations.

One of the objects of the invention is to provide a single circuit over which both the burglar and fire alarm signals may be sent from the subscriber's station to the central station.

A further object of the invention is to provide a system whereby, should several subscribers' stations attempt to signal the central station at the same time, the signals from the various subscribers' stations will be successively received at the central station, and this is accomplished generally by providing means at the subscriber's station for repeating the signal indefinitely until the particular subscriber's station is released from the central station, whereupon the next subscriber's station in order has its signal impressed at the central station and when the second station is released, the signal from the third station is received, etc.

Another object of the invention is to provide local signals at the subscribers' stations which will be set into action as soon as the subscriber's station begins signaling the central station and continue in action as long as the subscriber's station continues to signal the central station, viz,—until the central station operator releases the subscriber's station.

Another object of the invention is to provide a system for the purposes described in which the operating circuits are of the normally closed type, whereby any interruption of the current will be signalized at the central station.

Another object of the invention is to make provision for the breaking of the main line circuits to the central office through the automatic switches of the subscribers' stations

in the event that the signal wheels of those stations should stop with the contact brushes on any of the contact plates.

The invention provides a central station in which is located a polarized relay, an audible signal and two distinct visual signals, one for the fire alarm indication and one for the burglar alarm indication, the signals being controlled by the polarized relay; a resetting device is also provided and a main line circuit connects the central station with the subscribers' stations, of which latter there may be any desired number connected in the line circuit, and each subscriber's station includes a single repeating impulsator or telegraphing device by means of which the station's predetermined identification signal is telegraphed by successive repetitions until received and noted at the central station, and by the central station operator the subscriber's station is released or reset; two distinct sets of switching devices, one for the burglar alarm and one for the fire alarm, are located at each subscriber's station and co-operative connections are provided between the switching devices and the impulsator and include a source of electrical energy for setting the impulsator into action to send out the impulses of the desired polarity into the main line circuit to actuate the polarized relay at the central station and thereby set the proper signal. Means are also provided under control of the central station operator for resetting the switching device and in turn stopping the action of the signaling device.

With other objects in view which will hereinafter more clearly appear the invention also resides in those novel details of construction, combination and arrangement of parts, all of which will be first fully described and then be specifically pointed out in the appended claims, reference being had to the accompanying drawings in which:—

Figure 1 is a diagrammatic view of a central station apparatus. Fig. 2 is a diagrammatic view of a subscriber's station (station A) showing the position of the parts when normal or inactive. Fig. 3 is a view similar to Fig. 2 of the apparatus of a second station (station B) showing the position of the parts during the sending of a burglar alarm. Fig. 4 is a view similar to Figs. 2 and 3 but showing the position of the parts when sending in a fire alarm. Fig. 5 is an enlarged detail view of one of the switches.

In the drawings like numerals and letters of reference designate like parts in all the figures and in the interest of clearness I shall first describe the construction and then 5 the operation of the fire and burglar alarm units at the respective stations where protection is desired, and also the coöperative connections with the same at the central station.

- 10 Each subscriber's station (the protected premises) includes what I shall hereinafter term the fire and burglar alarm set of apparatus and each of such sets of apparatuses includes two distinct circuit controllers 15 which, for convenience, I shall call the automatic switches A and B respectively, the automatic switch A coöperating with the fire alarm mechanism and the switch B coöperating with the burglar alarm mechanism. 20 In addition to the switches A and B there is provided a signaling device that includes a motor 1, whose shaft 2 carries signaling disks 3 and 4, one of the signaling disks 3 forming a coöperative part of the fire alarm 25 mechanism, while the other 4, coöperates with the burglar alarm mechanism. The signaling device also includes the fixed contacts 5 and 6 which coöperate with the spaced contacts 7 and 8 on the respective 30 disks 3 and 4, it being understood that the contacts 7 and 8 are grouped and arranged to make the proper combination of impulses in order to give the required signal of the particular station as will later more clearly 35 appear.

Each of the switches A and B includes a polarized armature 9, that is pivoted at 10, and normally lies in the position indicated in Fig. 2. Each of the armatures 9 carries 40 an arc plate that is provided with a series of insulated portions 11, and a set of contact portions 12, 13, 14, 15. Each switch also includes stops 16 and 17 for limiting the movement of the armature and it further includes 45 the operating magnets 18 and 19.

200 and 300 designate the line wires which run between the several stations.

The fire and burglar alarm apparatus of each subscriber's station also includes an 50 audible signal 20 for the burglar alarm and an audible signal 21, of a different type, for the fire alarm, which signals are located at any desired place on the protected premises, and furthermore each of the burglar and 55 fire alarm apparatuses includes a set of circuit closers 22 (of which there may be any number connected in parallel) for the burglar alarm and a suitable number of circuit closers 23 (any number of which may 60 be provided connected in multiple) for the fire alarm. The fire and burglar alarm set of each station also includes the main line relays 24 and 25, there being one provided for each line wire. The relay 24 includes 65 an armature 26 which is pivoted in a

manner to engage either the fixed contacts 27-28 or the fixed contacts 29-30 according to the position of the armature 26, it being understood that the armature is normally held by a spring (see Fig. 2) or otherwise in the position shown at Fig. 2.

Either or both of the switches A and B may be constructed so that the magnet 19 may act as a part of a relay, the core 31 of which coöperates with the armature 32 that 75 in turn coöperates with the fixed contact 33.

The circuit closers 22 each include a fixed contact 34 and a movable contact 35 which are adapted to be brought into engagement when the signal is to be given. The contact 34 is in electrical connection with one of the windings of the magnets 18 and 19 through a wire 36, that winding of the magnets 18 and 19 being in turn connected through a wire 37 with the fixed contact 38 of the switch B. The fixed contact 34 is also electrically connected with the fixed contact 33 by a connection 39. The armature 32 is electrically connected with the wire 40 that connects with the wire 41 which leads to 90 the movable contact 35 of the circuit closer 22, the wire 40 also connecting to the positive pole of the local battery 42. The battery 42 has its negative pole connected by a wire 43 to the fixed contact 85 of the switch A. The wire 41 connects electrically with the fixed contact member 5.

45 and 46 are the main line batteries of the burglar and fire alarm set. The battery 45 has its positive pole connected by a wire 47 100 with the contact 5 and its negative pole connected by a wire 48 with the contact 30 of relay 24, the contact 29 of which relay is connected by a wire 49 with the fixed contact 50 of the switch B. The opposed fixed contact 51 of that switch is connected by a connection 52 with the second winding of the magnets 19 and 18 of switch B, which winding is also connected by a connection 53 to the incoming connection 301 of the line wire 110 300 on the side of the particular station nearest the central station. The incoming line wire connection 201 of a station joins electrically with the armature 26 of the relay 24, while the outgoing line wire connection 115 202 connects with the contact 27 of that relay. The incoming line wire 301 of a station connects with the armature 54 of the relay 25, while the outgoing line wire 302 of that station connects with the fixed contact 120 55 of the relay 25.

The construction of the relays 24 and 25 is substantially identical. The relay 25 is also provided with fixed contacts 56 and 57 that correspond with the contacts 29 and 30 of 125 relay 24. The contact 56 of relay 25 is connected through a connection 58 with the fixed contact 50 of switch A, while the contact 51 of that switch connects through a wire 59 with the second winding of the mag- 130

nets 18 and 19 of switch A, which winding is also connected through a connection 60 to the incoming line wire connection 201.

The fire alarm circuit closers 23 each include a fixed contact 61 and a movable contact 62, the contact 61 being connected through a connection 63 with one of the windings of the magnets 18 and 19 of switch A, the said winding being in turn connected 10 through a connection 64 with the fixed contact 38 of switch A.

The movable contact 62 of the fire alarm circuit closer is connected through a wire 65 with the fixed contact 6 of the signaling 15 mechanism. The stop 17 of circuit switch B is electrically connected through a connection 66 with the positive pole of the local battery 67, and the armature 9 of the switch B is electrically connected through a connection 68 with the relay magnet 24, which magnet is also connected through a connection 69 with the negative pole of the local battery 67. The stop 17 of switch A is connected by a connection 70 with the winding 25 of the magnet 25, such winding being also connected by connection 71 to the positive pole of the local battery 67. The fixed contact 72 of switch A is connected through 73 to the wire 74 which leads down to one terminal of the motor 1, and the fixed contact 72 of switch B is similarly connected through a wire 73 to the wire 74. The contact 44 of the switch B is connected by a wire 77 with the audible signal 20, which 35 signal is also connected by a wire 78 to auxiliary contact 79 on the disk or impulse wheel 3. The contact 75 of switch B is connected by a wire 80 to the wire 48 which is in electrical connection with the main line 40 battery 45. The contact 81 of switch B connects through a wire 82 to the incoming main line connection 301, while the contact 83 of switch B connects through a wire 84 with the set of contacts 7 on the impulse 45 wheel 3. The contact 85 of switch B connects through a wire 86 to the negative pole of the local battery 42. The contact 81 of switch A connects through a wire 87 to the incoming line connection 201, while the contact 50 83 of switch A connects through a wire 88 to the set of contacts 8 on the impulse wheel or disk 4. The contact 75 of switch A connects through a wire 89 to the audible signal 21 which is in turn connected through a wire 90 to the auxiliary contact 91 on the impulse wheel 4, while the contact 44 of switch A connects through a wire 92 to the wire 93 which connects to the negative pole 55 of the main line battery 46. The wire 92 also connects through a branch 94 with the contact 76 of switch A. The contact 76 of switch B connects through a wire 95 to the wire 48. The armature 9 of switch A connects through a wire 96 to the negative pole 60 of the local battery 67.

The switch A and B of the last station includes a pair of contacts 97 and 98 for a purpose hereinafter explained.

The central station wiring.—At the central station there is provided a polarized relay, 70 two distinct visual signals, and an audible signal, one of the visual signals 101 coöperating with the burglar alarm mechanism and the other 102 coöperating with the fire alarm mechanism, while the audible signal 103 is 75 operated when either a fire or burglar alarm is signaled. The polarized relay includes the coils 104 and 105 (having two distinct windings) with the usual pole pieces that coöperate with the balanced armature 106. 80 The armature 106 is provided with lever contacts 107 that are in electrical connection with one pole of the local battery 108, the other pole of which is connected by connection 109 with each of the visual signals 85 101—102. Each of the signals 101—102 is wired up, by wires 110, with separate contacts 111—112 that coöperate with opposed ones of the contacts 107 at times to close the circuits through the visual signals 90 as will later more clearly appear. The central station polarized relay is also provided with fixed contacts 113 that are electrically connected at 114 to the audible signal 103 which signal is in turn connected by a wire 95 115 to the wire 109 that is itself electrically connected with the negative pole of the local battery 108.

Coöperative with the fire and burglar alarm mechanism there is provided in the 100 central station, a hand switch 116 of the double type, such switch having a pair of levers 117—118 to coöperate with the fixed contacts 119—120. The lever 118 is connected by a wire 121 to the local winding 105 of the polarized relay coils 104—105. This same winding of the relay magnets is also connected by a wire 122 to a local battery 123 which is in turn connected by a wire 124 to the contact 120, of the switch 116, where- 110 by there is provided a normally closed circuit through the balancing coils of the relay. One terminal of the operating or main line winding of the coils of the relay magnets is connected by a wire 125 to the line wire connection 303, while the other terminal of such winding is connected by wire 126 to the lever 117 of the switch. The contact 119 of switch 116 is wired up at 127 with the contact 128 to another single throw hand 115 switch, the lever 129 of which is connected by a wire 130 that connects to the outgoing line wire 203.

131 is a key which is electrically connected at 132 with the wire 130 and is normally 125 in an open circuit position. The contact 133 of the key is connected by a wire 134 to a main line battery 135, the other pole of which is connected by a wire 136 to the line wire connection 303. 137 is a second key 130

which is electrically connected at 138 to the outgoing line wire 303 and the fixed contact 139 of which key is connected by wire 140 to a main line battery 141, which is in turn connected by a connection 142 to the wire 130.

- Operation of the burglar alarm mechanism.*—Assume now that one of the burglar alarm contacts 35 of a station (Fig. 3) is moved to close the circuit with contact 34 of that station. The instant this occurs, the local battery 42 will send out a current via wires 40—41 to circuit closer 22, over contacts 35 and 34 and via wire 36 through the local winding of the magnets 18 and 19 of switch B, the current passing over wire 37 to contact 38, across contact 15 (the armature and the segmental switch member being in the normal position, see Fig. 2, at the instant of closing) to contact 76, over wire 95, and a part of wire 48 back to the battery 42 via connection 43*, thus establishing a circuit which will energize the magnets 18 and 19 and rock over the armature of switch B to the position shown in Fig. 3. At the instant the circuit is closed through the contacts 35 and 34, the magnets 18 and 19 of switch B are energized thereby moving lever 32 of the relay into the position shown in full lines in Fig. 3 to close the local circuit path from wire 40 to wire 39 and thereby maintain the local circuit current through the magnets 18 and 19 until the circuit is broken by the rocking over of the armature 9 of switch B to the position shown in Fig. 3 to interrupt the circuit at the contacts 38 and 76. This takes care of the condition which would exist were the circuit immediately broken again at the contacts 35 and 34, so as to insure a sufficient energizing of the magnets 18 and 19 to throw the armature 9 over even though the circuit be closed but momentarily at the contacts 32 and 34. If the local circuit current from the battery 42 via contacts 35—34 or relay contacts 32—33 is not sufficient to throw over the armature 9 to its working place, indicated in Fig. 3, switch B, the main line battery 45 is brought into operation to make a short local circuit before being used for signaling purposes *i. e.* before the path from the battery 45 is opened up to the central station. The momentary circuit afforded by the main line battery only comes into action in the event that the local circuit has not completed the throwing over or rocking of the armature 9 of the switch B to its working position. If the switch B remains in its normal position, a circuit will be established from the main line battery 45 via wire 47, wire 41, across contacts 35 and 34 (which are still closed) through the local coils of magnets 18 and 19 and via contacts 38, 15 and 76 and wires 95 and 48, back to the battery

45. This last current is sufficient to throw the magnet and the arch switching arrangement over and the use of the main line battery 45 for establishing this local circuit may or may not be employed, but is illustrated to show that the main line battery may, while otherwise idle, be employed for this purpose. Now assume that the armature 9 of switch B in Fig. 3 has been thrown over to the full line position shown in that figure. This opens a new path for the local circuit from battery 42 at the same time the first local circuit, above described, is broken by an insulated portion of the arc member coming in between the contacts 38 and 76. The new circuit now opened up has for its object to start the motor 1 into action. This circuit emanates from the local battery 42 and passes via wire 99, to motor 1, and from thence over wires 74—73 to contact 72, of switch B, over conducting plate 15, to contact 85, and back to battery 42 via wire 86. This current starts the motor into operation to turn the signaling disks 3 and 4 and remains in operation so long as the circuit is closed between contacts 72 and 85. When the armature 9 of switch B was rocked over to the position in Fig. 3, a circuit was closed between it and the stop 17 thereby permitting a current to flow from battery 67 via wire 66, stop 17, armature 9, wire 68, to magnet of the main line relay 24, and from thence back to battery 67 via wire 69. This circuit is kept closed until the apparatus is reset. The coil of the relay 24 having become thus energized, draws over the armature 26 to engage the contacts 29 and 30 as shown in full lines in station B. The local circuit through the motor 1 starts it into operation as before described, thereby turning the signaling disks or wheels 3 and 4 to successively bring the various contacts 7—79 into engagement with the fixed contact 5 and the contacts 8—91 into engagement with the fixed contact 6. Every time one of the contacts 7 or 79 comes into engagement with the fixed contact 5, a current impulse flows from the battery 45 through brush or fixed contact 5, the contact 7 or 79, as the case may be, on the wheel 3. Assume that one of the contacts 7 is now in engagement with the brush or fixed contact 5 the current then flows from battery 45 via wire 47, contacts 5 and 7 to wire 84 and through that wire to contact 83 of the switch B. Inasmuch as the circuit is closed between contacts 83 and 81 of the switch B (the closing being effected via the conducting segment 14) the current passes into wire 82 and flows into the line wire connection 301 that is in circuit with the line wire 300 on the central station side of the apparatus; the current now flows along wire 300 through wire 302—301 of any stations that may be between the sta-

tion indicated in Fig. 3 and central station (the station indicated in Fig. 2 for example); via line wire 300 that is located between the station indicated in Fig. 2 and the central station into wire 303 of the central station. The current passes through the central station apparatus from wire 303 to wire 203, via wire 125, relay magnets 104-105, wire 126, switch contacts 117-119, wire 127, switch contacts 128-129 and wire 130. From wire 203 the current passes into line wire 200 and from thence through the main line wire connections 201-202 of the intermediate stations and line 200 to incoming line wire 201 of Fig. 3. Passing through wire 201 of station B, the current now passes across main line relay armature 26 via contact 30 to wire 48 and return to battery 45. Whenever the contact 79 engages the brush 5, the current from the main line battery 45, flowing via wire 47, contacts 5 and 79, and wire 78, passes through the audible signal (bell) 20 to ring it, the current flowing from the signal 20 to wire 77 over contacts 44, 13, 75, and wire 80, back to wire 48, and battery 45, thus alarming the inmates of the protected premises, (Fig. 3) that the burglar alarm mechanism has been set into operation.

It will be observed that the action of the signaling wheel 3 is to alternately signal the central station via contact 7 and operate the signal 20 on the protected premises via the contact 79. In other words, a signal is sent into the central station and then the local signal is operated, and subsequently the central station signal, until the apparatus is reset.

Operation of central station apparatus on burglar alarm signal.—The burglar alarm contacts 35-34 of some protected premises station (say the station indicated in Fig. 3) having been closed and a current sent out via main line wires 300, and return via wire 200, from the main line battery 45 of that station, as before described, a circuit has been established at the central station. It should be understood right here that the contact wheels 3 and 4 of each station have their contacts 7 and 8 differently arranged at each station so as to have each station give a different telegraphic signal. The current entering the central station over line 300 and its connection 303 at the central station, passes through the operating winding of the polarized relay, passing through the coils 104-105 as before described. Lever 106 of the polarized relay is normally kept in a balanced position by suitable springs in the usual manner, it being understood that those parts of the relay indicated in solid black are of insulating material. When the burglar alarm signal of telegraphic impulses comes in and the main

line current passes through the coils 104 and 105, the lever 106 is attracted toward, say the coil 105, at the central station. This causes one of the levers 107 to close the circuit contacts 111 and 113 respectively, thereby permitting the local battery 108 to send a current via contact 111, wire 110 to visual signal 101 (in this instance the same may be a blue bulb), and back to battery 108 via wire 109, a branch circuit being formed via contact 113 through one of the wires 114 to the audible signal 103 and back to battery via wire 115. Thus each impulse that is received in the central station causes a corresponding operation of the audible and visual signals 103 and 101 respectively. This operation continues to occur indefinitely until the watchman at the central office has taken note of the signal and reset the instruments as will be hereinafter described.

I desire it understood that while I have indicated the visual signals as incandescent bulbs and the audible signals as bells or buzzers, nevertheless, any standard type of signal that may be desired can be employed in lieu thereof.

123 is a balancing battery which sends a continuous current through a second or local winding of the polarized relay via wires 122-124-121 and switch contacts 120-118, for the purpose of balancing the effect of the normal main line current.

A battery 100 at the last or terminal station is connected by a wire 142 with the fixed contact 97 of switch A and by wire 143 with fixed contact 97 of switch B. The fixed contacts 98 of switches A and B are connected to the respective line wire connections 302 and 202, whereby a constant current is normally maintained in the line wires 200 and 300 and through the working windings of relay coils 104-105 at the central station.

The circuit of the battery 123 is opened at switch 118 by the operator at the central station as soon as the signal bell 103 rings in order to get the signal clear as will be later more fully explained.

Resetting of the burglar alarm signaling apparatus.—In order to reset the apparatus which has been sending in the burglar alarm signal, I have provided, at the central station, a battery 135 and a key 131. As soon as the burglar alarm signal has been received the attendant at the central station temporarily opens the circuit at switch 129, and depresses the key 131. This causes the battery 135 to send out a current via wire 134, contact 133, switch lever 131, wire 132, 125 into wire 203, and from thence into line wire 200. The current returning from line wire 300 via 303, wire 136 to battery 135. This current entering station B passes over wire 201, armature 26, wire 49, across con-

tacts 50, 12, 51, over wire 52, through main line windings of magnets 18 and 19, over wire 53, and back into line wire 301, thereby energizing such magnets to reverse the position of the armature 9 and restore it to its normal location, and thereby break the circuits at contacts 72-85, 81-83, 44-75, 50-51, and making the circuits at contacts 38-76 of switch B.

- 10 *Operation of the fire alarm mechanism.*—Let us assume that a fire occurs at a station which causes the closing of one or more of the circuit closers 23 (it being understood that any desired number connected in parallel may be employed) at the contact 62-61. Upon closing of the contact 62-61, a circuit is established from the main line battery 46 via wire 65, contacts 62-61, wire 63, local winding of magnets 19 and 18 of automatic switch A via wire 64, across contacts 38-12 and 76 of switch A (Fig. 4), to wire 94 through which the current passes via wire 93, back to the battery 46, the battery 46 in this instance acting as the local energizing battery. This current energizes the magnet coils 19 and 18 and rocks over the armature 9 of switch A to the position shown in Fig. 4, thereby breaking the circuits between the contacts 38 and 76, and making the circuits between the contacts 44-75, 81-83, 72-85, 50-51, and 9-17. Upon throwing over of the armature 9 of switch A to the position shown in Fig. 4, a current is sent out by battery 42 via wire 99 to motor 1 and return via wire 74, 73, contacts 72-12-85, wire 43 back to battery 42, thus setting the motor 1 into operation to turn the signaling disks 3 and 4. At the same time, a circuit is established from battery 67 via wire 71, through the winding of relay 25, and via wire 70, contact 17, armature 9 and wire 96, back to battery 67, thus operating the relay 25 to cause its armature to move over into engagement with the contacts 56 and 57, thereby breaking the main line circuit at contact 55, see Fig. 4. Current impulses are then sent out by the disk 4. As the contacts 8 come into engagement with the brush contact 6, a current will flow from the battery 46 over brush and contact 6, 8, wire 88, contacts 83-14-81, wire 87, to line wire connection 201, and from thence over line wire 200, through the wires 202 and 201 of the intermediate stations (assuming that the intermediate station apparatus is all in its normal position) to the central station, the impulse coming into the central station over wire 200 instead of over wire 300 as in the case of the fire alarm signal, the current passing through the central station apparatus via wires 203, 130, 127, switch members 119, 117, wire 126, operating windings of coils 105-104, over wire 125, and wire 303, to main line wire

300, and over that wire (and the intermediate station wires 301 and 302) back into wire 301, see Fig. 4, across armature of relay 25 to contact 57 and via wire 93, return to battery 46. This causes an operation of the central station apparatus as later described. If any of the intermediate stations, say station B for example, is sending in a signal to the central station at the time a signal is formed at the station represented in Fig. 4, as for example if the station indicated in Fig. 3 is sending in a burglar alarm, all stations beyond the station indicated in Fig. 3 will be operatively cut off from the central station during the time that station indicated in Fig. 3 is sending in the signal, for example, during the time the circuit is open at the station indicated in Fig. 3, at main line relay 24,—but as soon as the intermediate station apparatus has been reset by the attendant at the central station as hereinbefore described with regard to the station indicated in Fig. 3 the station indicated in Fig. 4 will be brought into action and the signal impelled by the battery 46 will be indicated at the central station. During the operation of the signaling disk 4, when the contact 91 engages the brush 6, a current will be impelled from the main line battery 46 over brush 6, contact 91, and local wire 90, to the fire alarm signal 21 at the local station affected, and from that signal the current passes via wire 89, contacts 75-13-44, and wires 92-93, back to battery 46, thus operating alternately the local fire alarm signal at the affected station and the indicating apparatus at the central station.

Operation of central station apparatus on fire alarm signal.—The fire alarm signal coming into the central station over wire 200 and out through wire 300 upsets the balance of the central station relay correspondingly and throws the armature 106 over to the position against the pole piece of the magnet section 104 thereby opening the circuits at 110 the right and closing them at the left through contact lever 107 and contacts 112-113. The closing of the circuits at contacts 112-113 at the left of the relay levers 107 causes the battery 108 to send out 115 a divided current through wires 110-114 via contacts 112-113 to the visual signal 102 and the audible signal 103, the current returning through wires 109 and 115 to the battery 108.

It should be understood that whenever a signal comes into the central station, the attendant immediately breaks the local circuit of battery 123 by opening the contacts 118 and 120 so that the incoming signal may be 125 taken clear without interference by the battery 123 which is no longer required for balancing during the sending in of a signal.

It should be understood that when the switch 116 is thrown over, the circuit via contacts 117-119 is not broken.

Resetting of fire alarm apparatus.—In order to reset the fire alarm apparatus it is necessary that the central station send out a current that flows in the same direction as did the signaling current, namely, so that it will leave central station through wire 300, 10 and enter through the wire 200. This is accomplished by the battery 141. Upon closing the key 137 against the contact 139, the battery current flows out through wire 140 over contacts 139, key 137, wire 138, into line wire 300 via wire 303, and returns through wire 200 to battery 141, via wires 203 and 130. Before depressing the key 137, it should be understood that the circuit through the relay 20 magnets of the central station is broken by opening the switch 129. The current, flowing out through line wire 300 from the central station battery 141, enters the station through wire 301, passing to armature 54 of relay 25, and over this armature via wire 58, contacts 50, 15, 51, wire 59, through magnets 18 and 19 (in a direction reverse to the local current), via wire 60 to line wire connection 201 and back to central station, 30 over line wire 200. The energizing of the magnets 18 and 19 by this reverse current restores the automatic switch armature A (Fig. 4) to its initial or normal position (see for instance the position in Fig. 3). 35 The restoration of the switch A to its normal position breaks the circuits between 75 and 44, between 83 and 81, between 72 and 85, between 50 and 51, and also between 9 and 17, thus releasing the relay 25 and permitting the spring to draw the armature back against the contact 55, and disconnect contacts 56 and 57 as well as breaking the motor circuit and the circuit to the local alarm. This restores the station to its normal position, it being understood of course, 45 that in the meantime the circuit at the circuit closer 23 has been opened. The opening of the circuit at the circuit closers 22 and 23 is done either automatically after a given period of time or manually as may be found desired and since the method of opening these contacts forms no part of my present invention a detail description and disclosure of a means for accomplishing this 55 act is not made.

My present apparatus is particularly designed for use in connection with other auxiliary apparatus in a complete system which forms the subject matter of my application filed on the 7th day of November, 1914, Serial No. 870,751, and I desire it understood that changes in the details of construction, combination and arrangement of parts may be made without departing from

the spirit of the invention and scope of the 65 appended claims.

What I claim is:—

1. In a system of the class described, a central station and a set of subscribers' stations, a main line circuit connecting the respective stations, a signaling device at each subscriber's station for sending out telegraphic signals into the main line circuit, electromagnetically operated automatic switching devices at each subscriber's station for bringing said signaling device into action, there being at least two automatic switches at each subscriber's station, burglar alarm circuit closers coöperating with one of said switches, and fire alarm circuit 70 closers coöperating with the other of said switches, main line sources of energy at the subscribers' stations, coöperative connections between said switches and said sources of energy for bringing said sources of energy 75 into operative relation with said signaling devices to send out the signal impulses into the main line circuit upon closing the burglar or fire alarm circuit closers at a station, and signal receiving apparatus at the 80 central station and means separate from said circuit closure and coöperating with said automatic switch devices for maintaining their operative circuit closed a definite time regardless of the time of duration of the closing of said circuit closers.

2. In a system of the class described, a central station and a set of subscribers' stations, a main line circuit connecting the respective stations, a signaling device at each subscriber's station for sending out telegraphic signals into the main line circuit, automatic switching devices at each subscriber's station for bringing said signaling device into action, there being at least two 100 automatic switches at each subscriber's station, burglar alarm circuit closers coöperating with one of said switches, and fire alarm circuit closers coöperating with the other of said switches, main line sources of energy 105 at the subscribers' stations, coöperative connections between said switches and said sources of energy for bringing said sources of energy into operative relation with said signaling devices to send out the signal impulses into the main line circuit upon closing the burglar or fire alarm circuit closers at a station, and signal receiving apparatus at the central station, and means at each subscriber's station for cutting out of the 110 circuit the succeeding stations to the one whose signal is being transmitted to the central station.

3. In a system of the class described, a central station and a set of subscribers' stations, a main line circuit connecting the respective stations, a signaling device at each subscriber's station for sending out tele-

- graphic signals into the main line circuit, electromagnetically actuated automatic switching devices at each subscriber's station for bringing said signaling device into action, there being at least two automatic switches at each subscriber's station, burglar alarm circuit closers coöperating with one of said switches, and fire alarm circuit closers coöperating with the other of said switches, main line sources of energy at the subscribers' stations, coöperative connections between said switches and said sources of energy for bringing said sources of energy into operative relation with said signaling devices to send out the signal impulses into the main line circuit upon closing the burglar or fire alarm circuit closers at a station, and a branch circuit around said burglar alarm circuit closers and including means coöperating with said switching device for maintaining the energization of the electromagnetic operating means of said switching device in the event that said burglar alarm circuit closers are but momentarily closed, and signal receiving apparatus at the central station, and means at the central station coöperating with the switching devices at the subscriber's station for resetting the subscriber's station apparatus.
4. In a system of the class described, a central station and a set of subscribers' stations, a main line circuit connecting the respective stations, a signaling device at each subscriber's station for sending out telegraphic signals into the main line circuit, automatic switching devices at each subscriber's station for bringing said signaling device into action, there being at least two automatic switches at each subscriber's station, burglar alarm circuit closers coöperating with one of said switches, and fire alarm circuit closers coöperating with the other of said switches, main line sources of energy at the subscribers' stations, coöperative connections between said switches and said sources of energy for bringing said sources of energy into operative relation with said signaling devices to send out the signal impulses into the main line circuit upon closing the burglar or fire alarm circuit closers at a station, and signal receiving apparatus at the central station, and means at each subscriber's station for cutting out of the circuit the succeeding stations to the one whose signal is being transmitted to the central station, and means at the central station coöperating with the switching devices at the subscriber's station for resetting the subscriber's station apparatus.
5. In a system of the class described, a central station and a set of subscribers' stations, a main line circuit connecting all of said stations, means at the end of the system for maintaining a normal closed circuit current in said main line circuit, a signaling relay at the central station in said main line circuit, means at the central station coöperative with said relay for normally balancing said normal closed circuit current, a signaling apparatus at each subscriber's station normally disconnected from said main line circuit, and means at the subscriber's station coöperative with said signaling apparatus, and including normally open circuit closers, for bringing said signaling apparatus into circuit with the central station and cutting out the succeeding subscriber's station from connection with the central station upon closing one of said circuit closers.
6. In a system of the class described, a central station and a set of subscriber's stations, a main line circuit connecting all of said stations, means for maintaining a normal closed circuit current in said main line circuit, a signaling relay at the central station in said main line circuit, means at the central station coöperative with said relay for normally balancing said normal closed circuit current, a signaling apparatus at each subscriber's station normally disconnected from said main line circuit, and means at the subscriber's station coöperative with said signaling apparatus, and including normally open circuit closers, for bringing said signaling apparatus into circuit with the central station and cutting out the succeeding subscribers' stations from connection with the central station upon closing one of said circuit closers, said last named means including an automatic switching device, said automatic switch device including operating magnets having two distinct windings, a local battery circuit connected with one of said windings and with said circuit closer, and a main line circuit branch connecting the other of said windings with the main line, said circuit branch including normally open contacts at said switching device that are closable by said switching device when said switching device is operated by said local circuit.
7. In a system of the class described, a central station and a set of subscribers' stations, a main line circuit connecting all of said stations, means for maintaining a normal closed circuit current in said main line circuit, a signaling relay at the central station in said main line circuit, means at the central station coöperative with said relay for normally balancing said normal closed circuit current, a signaling apparatus at each subscriber's station normally disconnected from said main line circuit, and means at the subscriber's station coöperative with said signaling apparatus, and including normally open circuit closers, for bringing said signaling apparatus into circuit with the central station and cutting out the succeeding subscriber's station from connection with the central station upon closing one of said circuit closers.

- one of said circuit closers, said last named means including an automatic switching device, said automatic switching device including an operating magnet having two distinct 5 windings, a local battery circuit connected with one of said windings and with said circuit closer, and a main line circuit branch connecting the other of said windings with the main line, said circuit branch including 10 normally open contacts at said switching device that are closable by said switching device when said switching device is operated by said local circuit, and means at the central station for sending a reverse current 15 through the main line circuit, and said main line circuit winding of said switching device magnet for resetting said switching device and thereby restoring the subscriber's station apparatus to its initial position after 20 said local circuit has been opened.
8. In a system of the class described, a central station and a set of subscribers' stations, a main line circuit connecting all of said stations, means for maintaining a normal 25 closed circuit current in said main line circuit, a signaling relay at the central station in said main line circuit, means at the central station coöperative with said relay for normally balancing said normal closed 30 circuit current, a signaling apparatus at each subscriber's station normally disconnected from said main line circuit, and means at the subscriber's station coöperative with said signaling apparatus, and including normally open circuit closers, for bringing 35 said signaling apparatus into circuit with the central station and cutting out the succeeding subscribers' stations from connection with the central station upon closing one of said circuit closers, said last named 40 means including an automatic switching device, said automatic switching device including operating magnets having two distinct windings, a local battery circuit connected with one of said windings and with said circuit closer, and a main line circuit branch connecting the other of said windings with the main line, said circuit branch including 45 normally open contacts at said switching device that are closable by said switching device when said switching device is operated by said local circuit, and means at the central station for sending a reverse current 50 through the main line circuit, and said main line circuit winding of said switching device magnet for resetting said switching device and thereby restoring the subscriber's station apparatus to their initial position after said local circuit has been opened, said subscriber's station signaling apparatus including two distinct sets of signaling contacts one for the main line circuit and another for a local circuit, and a local battery circuit including a signal and said other set of contacts whereby signals will be alternately impelled to the central station and to the local signal of the subscriber's station.
9. In a system of the class described, a central station and a set of subscribers' stations, a main line circuit connecting all of said stations, means for maintaining a normal closed circuit current in said main line 55 circuit, a signaling relay at the central station including a winding connected in said main line circuit, and a local balancing winding, a local balancing circuit at the central station connected with said balancing winding to hold said relay normally inoperative, two distinct sets of signals controlled by said relay, a signaling device at each subscriber's station, said signaling device including two distinct signaling disks, two automatic switching devices at each subscriber's station, and two main line sources of energy, one of said 60 switches and one of said sources of energy coöperating with one signal disk of said signaling device, and the other switch and source of energy coöperating with the other disk of the signaling device, burglar oper- 65
- one of said circuit closers, said last named means including an automatic switching device, said automatic switching device including an operating magnet having two distinct 5 windings, a local battery circuit connected with one of said windings and with said circuit closer, and a main line circuit branch connecting the other of said windings with the main line, said circuit branch including 10 normally open contacts at said switching device that are closable by said switching device when said switching device is operated by said local circuit, and means at the central station for sending a reverse current 15 through the main line circuit, and said main line circuit winding of said switching device magnet for resetting said switching device and thereby restoring the subscriber's station apparatus to its initial position after 20 said local circuit has been opened.
8. In a system of the class described, a central station and a set of subscribers' stations, a main line circuit connecting all of said stations, means for maintaining a normal 25 closed circuit current in said main line circuit, a signaling relay at the central station in said main line circuit, means at the central station coöperative with said relay for normally balancing said normal closed 30 circuit current, a signaling apparatus at each subscriber's station normally disconnected from said main line circuit, and means at the subscriber's station coöperative with said signaling apparatus, and including normally open circuit closers, for bringing 35 said signaling apparatus into circuit with the central station and cutting out the succeeding subscribers' stations from connection with the central station upon closing one of said circuit closers, said last named 40 means including an automatic switching device, said automatic switching device including operating magnets having two distinct windings, a local battery circuit connected with one of said windings and with said circuit closer, and a main line circuit branch connecting the other of said windings with the main line, said circuit branch including 45 normally open contacts at said switching device that are closable by said switching device when said switching device is operated by said local circuit, and means at the central station for sending a reverse current 50 through the main line circuit, and said main line circuit winding of said switching device magnet for resetting said switching device and thereby restoring the subscriber's station apparatus to their initial position after said local circuit has been opened, said subscriber's station signaling apparatus including two distinct sets of signaling contacts one for the main line circuit and another for a local circuit, and a local battery circuit including a signal and said other set of contacts whereby signals will be alternately impelled to the central station and to the local signal of the subscriber's station.
10. In a system of the character described, a central station and a set of subscribers' stations, a main line circuit connecting all of said stations, means for maintaining a normal current in said main line circuit whereby the same is normally a closed circuit, a signaling relay in the central station including a winding connected in said main line circuit, and a local balancing winding, a local balancing circuit at the central station connected with said balancing winding to hold said relay normally inoperative, two distinct sets of signals controlled by said relay, a signaling device at each subscriber's station, said signaling device including two distinct signaling disks, two automatic switching devices at each subscriber's station, and two main line sources of energy, one of said 55 switches and one of said sources of energy coöperating with one signal disk of said signaling device, and the other switch and source of energy coöperating with the other disk of the signaling device, burglar oper- 60

- ated circuit closers and operative connections between the same and one of the switches, fire operated circuit closers and co-operative connections between the same and the other of said switches, local battery circuits for the respective circuit closers, each of said switches including operating magnets having a local winding in the respective local circuit, and a main line winding in the main line circuit, said main line winding including switching terminals normally open at the respective switching device, and means for opening the main line circuit to stations beyond the nearest station to the central station which is sending in a signal.
11. In a system of the character described, a central station and a set of subscribers' stations, a main line circuit connecting all of said stations, means for maintaining a normal current in said main line circuit whereby the same is normally a closed circuit, a signaling relay in the central station including a winding connected in said main line circuit, and a local balancing winding, a local balancing circuit at the central station connected with said balancing winding to hold said relay normally inoperative, two distinct sets of signals controlled by said relay, a signaling device at each subscriber's station, said signaling device including two distinct signaling disks, two automatic switching devices at each subscriber's station, and two main line sources of energy, one of said switches and one of said sources of energy coöperating with one signal disk of said signaling device, and the other switch and source of energy coöperating with the other disk of the signaling device, burglar operated circuit closers and operative connections between the same and one of the switches, fire operated circuit closers and co-operative connections between the same and the other of said switches, local battery circuits for the respective circuit closers, each of said switches including operating magnets having a local winding in the respective local circuit, and a main line winding in the main line circuit, said main line winding including switching terminals normally open at the respective switching device, and means for opening the main line circuit to stations beyond the nearest station to the central station which is sending in a signal, and means operable at the central station for restoring said switching devices to their initial position to thereby reset the subscriber's station apparatus.
12. In a system of the class described, a central station and a plurality of subscribers' stations, a main line circuit connecting the respective stations and including a source of energy for maintaining a normal current in said main line circuit, a signal receiving apparatus at the central station including operating magnets having a winding con-
- nected in said main line circuit, and also including a local balancing winding, a local balancing circuit at the central station including said balancing winding; normally inoperative means at each subscriber's station for sending telegraphic signal impulses into the main line circuit to the central station, means at each subscriber's station for setting said signaling means into operation at times, means at each subscriber's station coöperative with said setting means for cutting the main line circuit to subscribers' station beyond, the signaling means of each subscriber's station when set being adapted to operate for an indefinite time regardless of whether or not the main line circuit of a particular station is open to the central station, and means at the central station for resetting the apparatus at the particular subscriber's station which is in operative connection with the central station and thereby bring the next succeeding station into connection with the central station whereby its signal may be received at the central station.
13. In a system of the class described, a central station and a plurality of subscribers' stations, a main line circuit connecting the respective stations and including a constant current source of energy, a signal receiving apparatus at the central station connected in the main line circuit and normally balanced so as to be non-operative by the normal main line current, a signaling device at each subscriber's station, said signaling device including a plurality of distinct signal sending sections, separate switching devices coöperative with each section, separate means at the subscriber's station for operating the respective switches to set the respective section of the signaling apparatus into connection with the main line circuit whereby the signals may be impulsed to the central station, and means controllable at the central station and coöperating with said switches for resetting the subscriber's apparatus.
14. In a system of the class described, a central station and a plurality of subscribers' stations, a main line circuit connecting the respective stations and including a constant current source of energy, a signal receiving apparatus at the central station connected in the main line circuit and normally balanced so as to be non-operative by the normal main line current, a signaling device at each subscriber's station, said signaling device including a plurality of distinct signal sending sections, separate switching devices coöperative with each section, separate means at the subscriber's station for operating the respective switches to set the respective section of the signaling apparatus into connection with the main line circuit whereby the signals may be im-

- pulsed to the central station, and means controllable at the central station and coöperating with said switches for resetting the subscriber's apparatus, and local signals at the 5 subscriber's station coöperative with the respective sections of the station's signaling apparatus whereby when the signaling apparatus of a station is set into operation a local signal will also be actuated.
- 10 15. In a system of the class described, a central station and a plurality of subscribers' stations, a main line circuit connecting the respective stations and including a constant current source of energy, a signal receiving apparatus at the central station connected in the main line circuit and normally balanced so as to be non-operative by the normal main line current, a signaling device at each subscriber's station, 15 said signaling device including a plurality of distinct signal sending sections, separate switching devices coöperative with each section, separate means at the subscriber's station for operating the respective switches 20 to set the respective section of the signaling apparatus into connection with the main line circuit whereby the signals may be impulsed to the central station, and means controllable at the central station and coöperating with said switches for resetting the 25 subscriber's apparatus, and means coöperative with the respective switching devices for breaking the main line circuit to stations beyond the particular station whose 30 signaling apparatus has been set into action, whereby only the station in operation nearest the central station will have its signals transmitted to the central station.
16. In a system of the class described, a central station and a plurality of subscribers' stations, a main line circuit connecting the respective stations and including a constant current source of energy, a signal receiving apparatus at the central station connected in the main line circuit and normally balanced so as to be non-operative by the normal main line current, a signaling device at each subscriber's station, said signaling device including a plurality of distinct signal sending sections, separate switching devices coöperative with each section, separate means at the subscriber's station for operating the respective switches to set the respective section of the 45 signaling apparatus into connection with the main line circuit whereby the signals may be impulsed to the central station, and means controllable at the central station and coöperating with said switches for resetting the subscriber's apparatus, and local signals at the subscriber's station coöperative with the respective sections of the station's signaling apparatus whereby when the signaling apparatus of a station is set 50 into operation a local signal will also be actuated, and means coöperative with the respective switching devices for breaking the main line circuit to stations beyond the particular station whose signaling apparatus has been set into action, whereby only the station in operation nearest the central station will have its signals transmitted to the central station. 70
17. In a system of the class described, a central station and a set of subscribers' stations, a main line circuit connecting said stations, a signal receiving apparatus in said main line circuit at the central station, signals at the central station controlled by said receiving apparatus, a signaling device at each subscriber's station, and a source of energy coöperative with the respective signaling device, an automatic switch at each subscriber's station for bringing said signaling device and its coöperative source of energy into connection with the main line circuit at times, whereby the station's signal may be impulsed into the main line to the central station, and means at the subscriber's station coöperative with said switching device for throwing it to the position to cause said signaling device to operate, and means controllable at the central station and coöperating with said switch for resetting the subscriber's apparatus. 80
18. In a system of the class described, a central station and a set of subscribers' stations, a main line circuit connecting said stations, a signal receiving apparatus in said main line circuit at the central station, signals at the central station controlled by said receiving apparatus, a signaling device at each subscriber's station, and a source of energy coöperative with the respective signaling device, an automatic switch at each subscriber's station for bringing said signaling device and its coöperative source of energy into connection with the main line circuit at times, whereby the station's signal may be impulsed into the main line to the central station, and means at the subscriber's station coöperative with said switching device for throwing it to the position to cause said signaling device to operate, and means coöperative with the respective station's switching device for disconnecting, from the main line circuit, the stations beyond during the time the respective station's signaling apparatus is transmitting signals. 95
19. In a system of the class described, a central station and a set of subscribers' stations, a main line circuit connecting said stations, a signal receiving apparatus in said main line circuit at the central station, signals at the central station controlled by said receiving apparatus, a signaling device at each subscriber's station, and a source of energy coöperative with the respective signaling device, an automatic switch at each subscriber's station for bringing said signaling device 100
20. In a system of the class described, a central station and a set of subscribers' stations, a main line circuit connecting said stations, a signal receiving apparatus in said main line circuit at the central station, signals at the central station controlled by said receiving apparatus, a signaling device at each subscriber's station, and a source of energy coöperative with the respective signaling device, an automatic switch at each subscriber's station for bringing said signaling device and its coöperative source of energy into connection with the main line circuit at times, whereby the station's signal may be impulsed into the main line to the central station, and means at the subscriber's station coöperative with said switching device for throwing it to the position to cause said signaling device to operate, and means coöperative with the respective station's switching device for disconnecting, from the main line circuit, the stations beyond during the time the respective station's signaling apparatus is transmitting signals. 110
21. In a system of the class described, a central station and a set of subscribers' stations, a main line circuit connecting said stations, a signal receiving apparatus in said main line circuit at the central station, signals at the central station controlled by said receiving apparatus, a signaling device at each subscriber's station, and a source of energy coöperative with the respective signaling device, an automatic switch at each subscriber's station for bringing said signaling device and its coöperative source of energy into connection with the main line circuit at times, whereby the station's signal may be impulsed into the main line to the central station, and means at the subscriber's station coöperative with said switching device for throwing it to the position to cause said signaling device to operate, and means coöperative with the respective station's switching device for disconnecting, from the main line circuit, the stations beyond during the time the respective station's signaling apparatus is transmitting signals. 115
22. In a system of the class described, a central station and a set of subscribers' stations, a main line circuit connecting said stations, a signal receiving apparatus in said main line circuit at the central station, signals at the central station controlled by said receiving apparatus, a signaling device at each subscriber's station, and a source of energy coöperative with the respective signaling device, an automatic switch at each subscriber's station for bringing said signaling device and its coöperative source of energy into connection with the main line circuit at times, whereby the station's signal may be impulsed into the main line to the central station, and means at the subscriber's station coöperative with said switching device for throwing it to the position to cause said signaling device to operate, and means coöperative with the respective station's switching device for disconnecting, from the main line circuit, the stations beyond during the time the respective station's signaling apparatus is transmitting signals. 120

ing device and its coöperative source of energy into connection with the main line circuit at times, whereby the station's signal may be impulsed into the main line to the 5 central station, and means at the subscriber's station coöperative with said switching device for throwing it to the position to cause said signaling device to operate, means controllable at the central station and coöperative with the switching device of the respective subscribers' stations for resetting the apparatus of the subscribers' stations.

20. In a system of the class described, a central station and a set of subscribers' stations, a main line circuit connecting said stations, a signal receiving apparatus in said main line circuit at the central station, signals at the central station controlled by said receiving apparatus, a signaling device at 20 each subscriber's station, and a source of energy coöperative with the respective signaling device, an automatic switch at each subscriber's station for bringing said signaling device and its coöperative source of energy into connection with the main line circuit at times, whereby the station's signal may be impulsed into the main line to the central station, and means at the subscriber's station coöperative with said switching device for throwing it to the position to cause 25 said signaling device to operate, and means coöperative with the respective station's switching device for disconnecting, from the main line circuit, the stations beyond during 30 the time the respective station's signaling apparatus is transmitting signals, means controllable at the central station and coöperative with the switch devices of the respective subscribers' stations for resetting 35 the apparatus of the subscribers' stations.

21. A central station and a set of subscribers' stations, and a main line circuit connecting the respective stations, a balanced relay at the central station connected in the 45 main line circuit, two distinct sets of signals controlled by said relay depending on the direction of the flow of current in said main line circuit; a signaling apparatus at each subscriber's station, and including two distinct sets of signaling disks, two distinct batteries at each subscriber's station, one coöperative with one signaling disk, and the other coöperative with the other signaling disk for sending current impulses in the 50 main line circuit according as one battery or the other is brought into circuit, two switching devices at each subscriber's station, one coöperative with one battery and the other coöperative with the other battery, and independent means for each switching device for operating the respective switching device to thereby bring the respective battery into operative relation to the main line circuit, whereby the signaling device 55 will transmit signaling impulses into the main line circuit in the direction for which the respective battery is designed to transmit, to thereby operate one or the other set 60

the main line circuit in the direction for which the respective battery is designed to transmit, to thereby operate one or the other set of signals at the central station.

22. A central station and a set of subscribers' stations, and a main line circuit connecting the respective stations, a balanced relay at the central station connected in the main line circuit, two distinct sets of signals controlled by said relay depending on the direction of the flow of current in said main line circuit; a signaling apparatus at each subscriber's station, and including two distinct sets of signaling disks, two distinct batteries at each subscriber's station, one coöperative with one signaling disk, and the other coöperative with the other signaling disk for sending current impulses in the main line circuit according as one battery or the other is brought into circuit, two switching devices at each subscriber's station, one coöperative with one battery and the other coöperative with the other battery, and independent means for each switching device for operating the respective switching device to thereby bring the respective battery into operative relation to the main line circuit, whereby the signaling device will transmit signaling impulses into the main line circuit in the direction for which the respective battery is designed to transmit, to thereby operate one or the other set of signals at the central station, and means controllable at the central station and coöperative with the switching devices of the subscribers' stations for resetting the subscriber's station apparatus.

23. A central station and a set of subscribers' stations, and a main line circuit connecting the respective stations, a balanced relay at the central station connected in the main line circuit, two distinct sets of signals controlled by said relay depending on the direction of the flow of current in said main line circuit; a signaling apparatus at each subscriber's station, and including two distinct sets of signaling disks, two distinct batteries at each subscriber's station, one coöperative with one signaling disk, and the other coöperative with the other signaling disk for sending current impulses in the main line circuit according as one battery or the other is brought into circuit, two switching devices at each subscriber's station, one coöperative with one battery and the other coöperative with the other battery, and independent means for each switching device for operating the respective switching device to thereby bring the respective battery into operative relation to the main line circuit, whereby the signaling device will transmit signaling impulses into the main line circuit in the direction for which the respective battery is designed to transmit, to thereby operate one or the other set 100

- of signals at the central station, and means at each subscriber's station controlled by the respective switching device for breaking the main line circuit connection with the stations beyond to thereby disconnect said stations beyond the particular station under consideration, from the central station until the apparatus of said particular station has been reset.
24. A central station and a set of subscribers' stations, and a main line circuit connecting the respective stations, a balanced relay at the central station connected in the main line circuit, two distinct sets of signals controlled by said relay depending on the direction of the flow of current in said main line circuit; a signaling apparatus at each subscriber's station, and including two distinct sets of signaling disks, two distinct batteries at each subscriber's station, one co-operative with one signaling disk, and the other co-operative with the other signaling disk for sending current impulses in the main line circuit according as one battery or the other is brought into circuit, two switching devices at each subscriber's station, one co-operative with one battery and the other co-operative with the other battery, and independent means for each switching device for operating the respective switching device to thereby bring the respective battery into operative relation to the main line circuit, whereby the signaling device will transmit signaling impulses into the main line circuit in the direction for which the respective battery is designed to transmit, to thereby operate one or the other set of signals at the central station, and means controllable at the central station and co-operative with the switching devices of the subscribers' stations for resetting the subscriber's station apparatus, and means at each subscriber's station controlled by the respective switching device for breaking the main line connection with the stations beyond to thereby disconnect said stations beyond the particular station under consideration from the central station until the apparatus of said particular station has been reset.
25. In a system of the character stated, a central station and a plurality of subscribers' stations, a single main line circuit connecting all of said stations; alarm signal sending apparatus including an impulsator at the subscribers' stations, signal receiving and indicating apparatus at the central station, means distinct from the pulsator at the subscribers' stations for operatively disconnecting the stations beyond the one whose signal is being received at the central station until said signal at the central station has been noted and the apparatus at the particular subscriber's station has been reset, and means controlled at the central station for resetting the subscribers' stations.
- In witness whereof I hereunto subscribe my name this twenty-fifth day of January, 1913.
- OTTO ASMUSSEN.
- Witnesses:
- CÉSAR A. DE LOSADA,
CARLOS M. SARRIA.
